UNITED STATES PATENT OFFICE.

LOUIS A. KING, OF SALEM, MASSACHUSETTS.

BOTTLE-OPENER.

No. 797,437.

Specification of Letters Patent.

Patented Aug. 15, 1905.

Application filed September 29, 1904. Serial No. 226,459.

To all whom it may concern:

Be it known that I, LOUIS A. KING, a citizen of the United States, and a resident of Salem, in the county of Essex and State of Massachusetts, have invented certain new and useful Improvements in Bottle-Openers, of which the following is a specification.

This invention relates to improvements in bottle-openers of the kind in which a cardboard cover is used as a stopper for milk-cans or similar receptacles; and it consists of a simple device for removing said cardboard cover from the can whenever it is desired to remove the contents of the can, as will hereinafter be described, reference being had to the accompanying drawings, where—

Figure 1 is a section of the neck of a milk-can, showing the bottle-opener in position for removing the cardboard stopper. Fig. 2 is a top plan view of the milk-can and the bottle-opener, and Fig. 3 is a perspective view of the bottle-opener.

Similar letters refer to similar parts wherever they occur on the different parts of the drawings.

A represents the neck of a glass bottle or milk-can as usual, provided with a removable cardboard stopper B.

a is the upper annular curved edge of the neck of the milk-can as usual.

The opener device consists of a twisted-wire handle C, preferably terminating as a looped end D.

I wish to state that I do not confine myself to this exact form of construction, as the parts C D may be made of wire or pressed out of plate metal, as may be most suitable or convenient.

The forward end of the handle terminates as sharp prongs E E, adapted to be pushed through the cardboard previous to the removal of the latter.

Above the prongs E E are arranged loops F F, extending forward of the sharp prongs E E and serving as a guard for preventing

the hand from coming in contact with the sharp points when manipulating the device.

Back of the loops F F are arranged upright rests G, against which may be placed the thumb or finger when the pointed ends E are pressed into the cardboard.

Back of the finger-rests G is a curved portion H, serving as a fulcrum for the handle and supporting it upon the curved edge a of the neck of the bottle after the points E have been inserted through the cardboard cover previous to prying out the latter by moving the handle in the direction shown by arrow in Fig. 1.

In using the device the operator takes hold of the handle and places his thumb or finger against the upright G and punctures the cardboard B by the sharp prongs E and lays the fulcrum portion H of the handle on the rounded edge a of the mouth of the can and prays the cardboard cover out of the can by bending the handle downward in the direction of the arrow shown in Fig. 1, causing the cover to be readily detached from the can.

What I wish to secure by Letters Patent and claim is—

1. A device of the class described, including a handle terminating in prongs, a guard extended beyond and in parallelism with the said prongs and having upright rests, and a fulcrum at the rear of said rests adapted to bear on the neck of a bottle.

2. A bottle-opener, including a handle having a separated end forming prongs, and a guard extended beyond the same and in parallelism therewith, upright rests arranged at right angles to the guard, and a fulcrum portion above the prongs intermediate the said rests and the handle.

In testimony whereof I have affixed my signature in presence of two witnesses.

LOUIS A. KING.
